UNITED STATES PATENT OFFICE.

ALBERT W. PEARSALL, OF LOWELL, MASSACHUSETTS, ASSIGNOR TO LAMSON CONSOLIDATED STORE SERVICE COMPANY, OF NEWARK, NEW JERSEY, A CORPORATION OF NEW JERSEY.

PNEUMATIC-DESPATCH-TUBE APPARATUS.

No. 894,045.

Specification of Letters Patent.

Patented July 21, 1908.

Application filed January 28, 1907. Serial No. 354,412.

To all whom it may concern:

Be it known that I, **ALBERT W. PEARSALL**, of Lowell, in the county of Middlesex and State of Massachusetts, have invented certain new and useful Improvements in Pneumatic-Despatch-Tube Apparatus, of which the following is a specification.

My invention relates to improvements in terminals for pneumatic despatch tube apparatus, and is particularly adapted for use in that type of pressure system shown and described in U. S. Letters Patent #551,602 issued to me Dec. 17, 1895, assignor to the Meteor Despatch Company.

15 The object of this invention is to provide a valve which will seat permanently by the action of the pressure within the system preventing any escape of said pressure and which valve is adapted to be operated by a carrier to open inwardly against the pressure within the system to permit the discharge of said carrier.

20 In the accompanying drawings which illustrate a construction embodying my invention, Figure 1 is a vertical sectional view of the terminal showing the valve held closed by the pressure within the system. Fig. 2 is a vertical sectional view of Fig. 1 showing the valve opened by a carrier about to discharge.

25 Like letters of reference refer to like parts throughout the several views.

A represents a tube connected with the delivery terminal B for the transmission of carriers to said terminal, and C is a transmission tube connecting with said terminal for the return of carriers. D is a valve controlling the delivery opening E in said terminal B which valve is pivoted at F and adapted to open inwardly. This valve is normally held closed as shown in Fig. 1 by the pressure within the system, which pressure is dormant when there are no carriers being transmitted.

30 A yoke G on the inner side of the valve carries a pin H which is mounted within a slot J in one end of a cam lever K, the opposite end of said cam lever being pivoted to the inner partition of the terminal at L, the whole forming a toggle-joint.

35 M is a buffer secured inside of the delivery opening E by screws N and adapted to receive the impact of the valve D when opened by a carrier. O is a spring adapted to assist in the closing of said valve.

40 The operation is as follows: A carrier in

transit through the tube A enters the terminal B, the front buffer of said carrier engaging the cam lever K, the pressure behind forcing said carrier to operate upon and move said cam lever K backward from the position shown in Fig. 1 to that shown in Fig. 2, and through the pin H operating in the slot J opening the valve against the pressure within the terminal and permitting the carrier to discharge through the opening E. After the carrier has passed the valve D the pressure within the terminal acting in conjunction with the spring O closes the valve D. The buffer M absorbs any sudden impact of the valve D upon the opening of the same by any carrier. The direction of the air currents during the transmission of the carrier is indicated by arrows (Fig. 2).

Having thus described the nature of my invention and set forth a construction embodying the same, what I claim as new and desire to secure by Letters Patent of the United States is:

1. In a terminal for pneumatic despatch tube apparatus, a valve controlling the delivery opening of said terminal and adapted to be normally held closed by the pressure within said terminal, and means operated by a carrier in transit in said terminal for opening said valve inwardly against said pressure to permit the delivery of said carrier.

2. In a terminal for pneumatic despatch tube apparatus, a valve controlling the delivery opening of said terminal and adapted to open inwardly and normally held closed by the pressure within said terminal, and pivoted means operated by a carrier in transit in said terminal for opening said valve to permit the discharge of said carrier.

3. In a terminal for pneumatic despatch tube apparatus, a swinging valve controlling the delivery opening of said terminal and adapted to open inwardly and normally held closed by the pressure within said terminal, and a cam lever adapted to be operated by a carrier in transit within said terminal for opening said valve against said pressure to permit the discharge of said carrier.

4. In a terminal for pneumatic despatch tube apparatus, a valve controlling the delivery opening and adapted to open inwardly of said terminal and normally held closed by the pressure in the terminal greater than the exterior atmospheric pressure, and mechanism arranged to be engaged and actuated by

the carrier arriving in said terminal and co-operating with and adapted to open said valve to permit the delivery of said carrier.

5. In a terminal for pneumatic despatch tube apparatus, a swinging valve controlling the delivery opening of said terminal and adapted to open inwardly and normally held closed by the pressure within said terminal, and a cam lever adapted to be operated by a carrier in transit within said terminal to open said valve against said pressure to permit the discharge of said carrier and provided with a

slot in which one end of said valve is pivoted—the other end being pivoted on the terminal.

15 In testimony whereof, I have signed my name to this specification in the presence of two subscribing witnesses, this 25th day of January A. D. 1907.

ALBERT W. PEARSALL.
